ABSTRACT: Containers are filled with a particulate product at a filling station and spillage of the produce is collected, conveyed to a point upstream from the filling station, and directed to flow towards the open ends of empty containers at a rate insufficient to fill a single container before that container is conveyed out of range for filling with spillage.

METHOD OF AND APPARATUS FOR FILLING CONTAINERS

BACKGROUND OF THE INVENTION

1. Field of the Invention

This invention pertains to automatically filling containers with a particulate product such as cut string beans, diced vegetables or sliced pickles. Spillage of the particulate product is collected downstream from a main filling station and conveyed upstream thereof to where it is fed into empty containers at a rate that allows only a portion of the container to be filled.

2. Description of the Prior Art

Filling machines are known which collect and return spillage to a main hopper and there the spillage is commingled with a fresh supply of particulate product. Problems have been encountered with such machines since it is possible for particles to spill and be recycled several times before being carried away in a container. Such recycling causes abrasive damage to the particles and delays further processing.

SUMMARY OF THE INVENTION

Spillage results from overfilling containers and to prevent multiple recycling of the spillage, it is necessary to retain original spillage in subsequent containers when it is fed thereto. By collecting and conveying the spillage from downstream of a filling station to a point upstream thereof, and directing the spillage to flow into empty containers at a rate that allows only a portion of the container to be filled, all of the spillage is carried away.

BRIEF DESCRIPTION OF THE DRAWINGS

FIG. 1 is a half longitudinal section of a container-filling apparatus embodying the present invention, taken to the left of line C-C.

FIG. 2 is a continuation of the half longitudinal section shown in FIG. 1, taken to the right of line C-C, with the extreme end portion being shown in side elevation and having portions broken away to show underlying structure.

FIG. 3 is a section taken on the line 3-3 of FIG. 1.

FIG. 4 is a section taken on the line 4-4 of FIG. 2.

FIG. 5 is a longitudinal section of a modified form of container filling apparatus embodying the present invention.

FIG. 6 is a section taken on the line 6-6 of FIG. 5.

DESCRIPTION OF THE PREFERRED EMBODIMENT

Looking now at FIGS. 1 and 2, a container-filling apparatus 10 is shown having a framework 12 consisting of standards and horizontal beams that support the apparatus. A pulley 14 (FIG. 1) is rotatably mounted on an upper level at the upstream end of the framework, while drive pulley 16 (FIG. 2) is rotatably mounted on an upper level at the downstream end of the framework. Idler wheels 18 (FIG. 1) and 20 (FIG. 2) are mounted at a lower level on intermediate framework standards and an endless conveyor belt 22 is trained about the pulleys and idler wheels. A multiplicity of support rollers 24 are positioned at narrow intervals along the upper length of framework to support the upper run of the endless conveyor belt.

Drive pulley 16 which drives the conveyor belt 22 is keyed to a shaft 26, shown in FIG. 2, and a spur gear 28 is mounted on the same shaft. Drive gear 30 meshes with the spur gear and is keyed to a shaft 32 upon which a driven sprocket 34 is fixed. A drive sprocket 36 is mounted on the drive shaft 38 of an electric motor 39 and a drive chain 40 is trained about the sprockets. Upon rotation of the drive sprocket, the drive chain turns the driven sprocket and drive gear which rotates the spur gear and drive pulley. Rotation of the drive pulley causes the upper run of conveyor belt 22 to move in the direction of arrow 42.

Guide rails 44 are supported by arms 46 (FIGS. 1 and 3) that extend upward from the framework 12 on opposite sides

of the conveyor belt 22. These rails provide lateral support for containers C which rest on the conveyor belt and are conveyed in the direction of arrow 42. Open ends 0 of the containers face upward to receive the particulate product with which the containers are filled.

Positioned along one side of the conveyor belt 22 is a vibratory feeder 48 (FIG. 1) which is fed by a supply hopper 50. This feeder is the main filling station whereby containers are filled with a particulate product and downstream therefrom is a product packer 52 (FIG. 2) that compacts the product within the containers. Downstream from the product packer is a second vibratory feeder 54 that is fed by a supply hopper 56. The second vibratory feeder fills the top portions of the containers C after the product has been compacted by the product packer.

A shaker section 58 is positioned downstream from the second vibratory feeder 54, as shown in FIG. 2, and guide rails 60 of the shaker section are separated from guide rails 44. The guide rails 60 are tilted slightly from vertical, as shown in FIG. 4, so that the open end 0 of the container C is inclined to a horizontal line 61 and the guide rails are connected by arms 62 to a shaking lever 64. The shaking lever is fixed to a pivot shaft 66 that is oscillated by a crank arm 68 and a cam rod 70 extends downward from the crank arm to rest upon a cam 72. The cam is keyed on a shaft 74 together with a driven sprocket 76 and a drive sprocket 78 is mounted on shaft 32. A drive chain 80 connects the sprocket wheels thus enabling the shaker section to be driven with the conveyor drive.

An idler roller 82 (FIG. 1) is rotatably mounted from the framework 12 at a location upstream from vibratory feeder 48 and beneath the support rollers 24. A drive roller 84 (FIG. 2) is mounted on shaft 74 and an endless conveyor belt 86 is trained about these rollers. The upper run of conveyor belt 86 travels in an upstream direction, as indicated by arrow 88, and a trough 90 is positioned about the upper runs of conveyor belts 86 and 22. Spillage from containers C falls into the trough where it is collected on conveyor belt 86 and then carried upstream.

Beneath roller 82 at the upstream end of conveyor belt 86 (FIG. 2) is a feed control system 92 that continuously weighs the spillage returned and regulates the rate of flow from feeders 48 and 54 in response to the spillage returned. This system includes a constant speed-weighing belt 94 that is mounted on one side of a scale arm 96 while on the opposite side of the arm is an electrical contact 98 and a weight 99 for balancing the arm to obtain a desired rate of feed. Spaced on opposite sides of the electrical contact are an upper contact 100 for reducing the rate of feed and a lower contact 102 that increases the rate of feed. These contacts are connected to a control box 104 that has manual control knobs 105 and 107 for regulating the feed rate independently of the scale arm. The control box is supplied with AC power through cable 106 and a lead cable 108 connects the control box with the controls of vibratory feeders 48 and 54. Control systems such as described are known as belt-weighing control systems and are standard commercial items so no further description is considered necessary. The Syntron Division of FMC Corporation at Homer City, Penn. manufactures such control systems.

Spillage returned by the constant speed-weighing belt 94 drops into a rotary elevator 110 that is located upstream from feeder 48. This rotary elevator is provided with a stationary structure that includes end plates 112 and 114 between which circular segments 116 and 118 extend. An opening 120 is provided between the circular segments at the bottom portion thereof, while at the top portion an opening 122 is provided with a funnel 123 suspended therefrom to direct spillage into the open ends 0 of containers C. A cylindrical drum 124 having radial pockets 126 is fitted about the circular segments and is rotatably supported on rollers 128 and 130. These rollers are mounted on shafts 132 and 134, respectively, and roller 130 is driven by a drive chain 136 that is trained about a sprocket 137 on shaft 134 and a drive sprocket 138 that is mounted on the drive shaft of an electric motor 139.

In operation, containers C move on belt 22 in the direction of arrow 42 to the vibratory feeder 48 where the containers are filled and then pass onto the product packer 52. Here the particulate material within the containers is compacted to approximately 80 percent of container volume and then the containers move to the secondary vibratory feeder 54 where they are again filled to the top. As the containers move further downstream, they move onto the shaker section 58 where they are tilted slightly to the horizontal and vibrated between the guide rails 60. Excess particulate product falls over the lower edge of the tilted container and spillage dropping from the containers at both vibratory feeders, product packer and shaker is collected within the trough 90 on the upper run of conveyor belt 86.

Conveyor belt 86 carries the spillage upstream and drops the spillage on the constant speed-weighing belt 94 that is balanced on one side of the scale arm 96. If the spillage returned by the conveyor belt is within a set limit, the scale arm will remain balanced and be conveyed into the rotary elevator 110. Should the spillage exceed the set limit, the scale arm will tilt causing the electrical contact 98 to make contact with the upper contact 100. This closes a circuit and reduces the rate of feed to vibratory feeders 48 and 54. As in the previous case, the spillage is conveyed into the rotary conveyor where it is collected in the radial pockets 126 and carried to the top opening 122. Here the spillage drops into funnel 123 and is redirected towards the open ends of empty containers passing under the funnel. The rate at which the spillage is fed to the containers is insufficient to fill a container before it is carried out of range of the funnel. Thus, the spillage does not overflow a second time and is carried away in the bottoms of the containers.

A modified form of the invention is illustrated in FIGS. 5 and 6 as a container-filling apparatus 140 of the rotary cylinder type. A base member 141 holds a pair of rollers 142 and 143 that rotatably support one end of a cylindrical shell 144. The opposite end of the shell is supported by a base member 145 that holds a pair of rollers 146 and one which is not shown. Drive means are provided to turn the roller, not shown, and thus the cylindrical shell is rotated upon the rollers.

Projecting radially inward from the inner surface of the cylindrical shell is a ring 147 at one end, a ring 148 spaced intermediate of the ends and a ring 149 at the opposite end of the shell. The intermediate ring separates the shell interior into a main filling compartment 150 and a spillage-filling compartment 151. Extending longitudinally of the shell are a plurality of flanges 152 that project inward at an acute angle with the inner surface of the shell and form pockets between the rings.

A support member 153 is positioned opposite one end of the cylindrical shell 144 while a similar support member 154 is positioned opposite the other end. A drive roller 155 is keyed to a drive shaft 156 that is held in place by the support member 153 and a driven roller 157 is keyed to a shaft 158 that is held in place by the support member 154. An endless conveyor belt 159 is trained about the drive and driven rollers for carrying containers C through the cylindrical shell in the direction of arrow 160. Tension in the conveyor belt is adjusted by an idler roller 161 at support member 153 and an idler roller 162 at support member 154.

Positioned over conveyor belt 159 and the line of containers C is an elongated bottomless trough 163 supported at one end by leg 164 and at the opposite end by leg 165. A divider plate 166 is fitted within the trough at a location opposite the intermediate ring 148 in the cylindrical shell 144 through which the trough extends. This divider plate separates the trough into a spillage funnel 167 and a main filling funnel 168, that direct a particulate material to flow towards the open end 0 of each container that passes below.

A stand 169 is positioned adjacent support member 153 and supports a motor 170. The motor is provided with an eccentric drive connection to which one end of a connecting rod 171 is

coupled. The other end of the connecting rod is attached to a feeder tray 172 that extends into the cylindrical shell 144 to the main filling compartment 150. The end of the feeder tray within the cylindrical shell is slidably supported on a bracket 173 extending outward from the trough 163. Thus, it will be seen that movement of the connecting rod causes the feeder tray to vibrate and thereby convey a particulate product along the tray. A hopper 174 is mounted at the end of the feeder tray extending outside of the cylindrical shell and supplies the particulate product for filling containers.

A motor 175 is located at the end of the cylindrical shell 144 adjacent support member 154 and is provided with an eccentric drive connection to which one end of a connecting rod 176 is coupled. The other end of the connecting rod is attached to a feeder tray 177 that extends into the cylindrical shell to the spillage-filling compartment 151. The end of the feeder tray within the spillage-filling compartment is suspended by cables 178 and 179 from the trough 163 and is thus free to vibrate. The feeder tray is positioned directly below conveyor belt 159 to receive spillage from containers C and convey the spillage upstream into the spillage-filling compartment.

Operation of the modified form of invention begins with conveying a line of containers C on conveyor belt 159 in the direction of arrow 160. Particulate product is fed from hopper 174 through feeder tray 172 to the main filling compartment 150. There the product falls to the bottom of the cylindrical shell 144 and is collected in the pockets formed by flanges 152. Rotation of the cylindrical shell elevates the particulate product until it spills over the flange into the main filling funnel 168. Here the product is directed towards the open end of each container that passes beneath the funnel. Spillage from the containers is collected on feeder tray 177 and conveyed upstream to spillage-filling compartment 151. There the spillage drops into the cylindrical shell and is collected in the pockets formed by the flanges. Rotation of the cylindrical shell elevates the spillage until it spills into the spillage funnel 167. There it is redirected towards the open ends of empty containers.

Although the best mode contemplated for carrying out the present invention has herein been shown and described, it will be apparent that modification and variation may be made without departing from what is regarded to be the subject matter of the invention as set forth in the appended claims.

Having completed a detailed description of the invention so that those skilled in the art could practice the same,

I claim:

1. A method of filling containers open at one end with a particulate product comprising the steps of: conveying the containers past a filling station; directing the particulate product to flow towards the open end of each container that passes the filling station; collecting spillage of the particulate product; conveying the spillage uncommingled with said particulate product at said filling station to a point upstream from the filling station, and redirecting the spillage to flow toward towards the open ends of empty containers at said point upstream from the filling station.

2. The method described in claim 1, including the steps of tamping the particulate product within each container at a station downstream from the filling station, directing additional particulate product towards the open end of each container at a station downstream from the tamping station, tilting each

65 container so that the open end thereof is inclined to the horizontal at a location downstream from the station where additional product was directed thereto, shaking each container to remove excess product therefrom, collecting spillage of particulate product from the tamping station, additional filling station, and tilting and shaking station, and conveying the spillage collected together with the spillage from the filling station to the point upstream therefrom where the combined spillage is directed towards the open ends of empty containers.

3. The method described in claim 1, wherein the containers are conveyed at an established rate of speed past the filling

station and the point upstream therefrom, the spillage is redirected towards the empty containers at a flow rate insufficient to fill each container before the container is conveyed out of range of the spillage flow, and the particulate product is directed to flow towards the partially filled containers at a flow rate sufficient to fill the remainder of each container as it passes the filling station.

4. The method described in claim 3, including the step of decreasing the flow rate of particulate product towards the containers at the filling station in proportion to an increase in the flow rate of spillage towards the empty containers.

5. Apparatus for filling containers open at one end with a particulate product, said apparatus comprising: means for moving said containers along a fixed path from an upstream position to a downstream position; filling means positioned along said fixed path for directing the particulate product to flow towards the open end of each container that passes the

filling means; means for collecting spillage of the particulate product along the fixed path; conveyor means for moving said spillage uncommingled with said particulate product at said filling means to a point upstream from the filling means, and means for redirecting the spillage to flow towards the open ends of empty containers at said point upstream from the filling means.

6. Apparatus as described in claim 5, including a feed control system that continuously weighs spillage and regulates the rate of flow from the filling means in response to the spillage weight.

7. Apparatus as described in claim 5, wherein said filling means includes a first portion of a cylindrical drum type filler and the means for redirecting spillage includes a second portion of the cylindrical drum-type filler located upstream of the container moving means from the first portion.
